COMBINED AQUARIUM AND BAR

Fred H. Fisher, Sylvania, Ohio

Application August 21, 1957, Serial No. 47,469

Term of patent 14 years

(Cl. D91—2)

The figure is a front perspective view of the combined aquarium and bar showing my new design.

The rear of the bar is substantially plain.

In the front, the end not shown is similar to the end illustrated.

I claim:

The ornamental design for a combined aquarium and bar, as shown and described.
